UNITED STATES PATENT OFFICE

110,966

DESIGN FOR A TEXTILE FABRIC

Benjamin M. Kaufman, New York, N. Y.

Application May 26, 1938, Serial No. 77,388

Term of patent 3½ years

To all whom it may concern:

Be it known that I, Benjamin M. Kaufman, a citizen of the United States of America, residing in the city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The design consists of a relatively wide herringbone pattern of heavy ribbed stripes embodying irregularly looped yarns irregularly spaced and presenting a fur-like appearance.

I claim:

The ornamental design for a textile fabric, substantially as shown and described.

BENJAMIN M. KAUFMAN.
